UNITED STATES PATENT OFFICE.

CHARLES LE GEYT FORTESCUE, OF PITTSBURGH, PENNSYLVANIA, ASSIGNOR TO WESTINGHOUSE ELECTRIC AND MANUFACTURING COMPANY, A CORPORATION OF PENNSYLVANIA.

TRANSFORMER AND WINDING.

1,129,464.

Specification of Letters Patent.

Patented Feb. 23, 1915.

Original application filed August 2, 1909, Serial No. 510,854. Divided and this application filed October 8, 1910. Serial No. 586,101.

To all whom it may concern:

Be it known that I, CHARLES LE G. FORTESCUE, a subject of the King of Great Britain, and a resident of Pittsburgh, in the county of Allegheny and State of Pennsylvania, have invented a new and useful Improvement in Transformers and Windings, of which the following is a specification, this application being a division of application Serial No. 510,854, filed August 2, 1909.

My invention relates to transformers and particularly to the windings of high-voltage transformers.

15 The object of my invention is to provide such a proportioning and distribution of coils as to maintain substantially the same length of mean turn for all coils and, at the same time, separate the coils from the core member to a greater or less degree, according to their potential. By "length of mean turn," as used herein, I mean the aggregate length of all turns of any coil divided by the total number of turns in the coil.

20 25 My invention is particularly applicable to transformers of the shell type.

In my co-pending application, Serial No. 510,854, filed August 2, 1909, of which this is a division I have shown and described 30 and claimed broadly a transformer coil arrangement in which the coils are spaced from the core member, to a greater or less degree, according to their potentials. I now desire to lay claim, specifically, to an adaptation of this general arrangement to transformers of the shell type.

Figure 1, of the accompanying drawings, is a front elevation of a shell-type transformer embodying my invention, certain 40 of the parts being broken away to disclose the coils. Fig. 2 is a plan view of the core and windings shown in Fig. 1, and Fig. 3 is a diagrammatic view showing the circuit connections for the winding of the other 45 figures.

Referring to the drawings, the structure here shown comprises a core 1, low-voltage coils 2 and high-voltage coils 3. The core member 1 is in the form of two hollow rectangular prisms 1^a and 1^b set side by side as shown in Fig. 2 and producing an intermediate core leg 1^c on which the transformer coils are mounted. The high-voltage coils are interposed between the low-voltage 55 coils and are relatively narrow, being, at

the same time, centrally located, relative to the adjacent walls of the core member, so that all the coils of the transformer have the same length of mean turn and are all concentric, while the high-voltage coils are 60 separated from the core member in all directions and the low-voltage coils are adjacent to the core member.

I do not wish to be restricted to the structure and arrangement illustrated since modifications may be effected within the spirit and scope of my invention.

I claim as my invention:

1. A transformer comprising a core having three substantially parallel legs, spaced 70 low voltage coils, and a plurality of relatively high voltage coils of graded widths having the same length of mean turn and surrounding the intermediate core leg.

2. A transformer comprising a core having 75 three substantially parallel legs, spaced low-voltage coils surrounding the middle core leg and occupying substantially the entire width of space between the outer and the intermediate core legs and relatively 80 high-voltage coils of unequal width surrounding the intermediate core leg between the low-voltage coils and spaced therefrom in the order of their widths and so connected as to locate the coils of highest voltage 85 midway between the low-voltage coils, all of said coils having the same length of mean turn.

3. A transformer comprising a core member, and a plurality of side-by-side coils of 90 different widths, the mean turns of the coils being equal in length and spaced equally from the core member.

4. A transformer comprising a core, and a plurality of side-by-side coils of different 95 widths connected in a series in which the coils succeed each other in the order of their widths, the mean turns of the coils being equally spaced from the core.

5. A transformer comprising a core member, and a plurality of side-by-side coils of 100 different widths surrounding the core member and located different distances from the portions of the core member surrounded thereby, the median lines of the corresponding sides of the coils lying in substantially the same plane which is parallel to the axes of, the coils.

6. A transformer comprising spaced low-voltage coils and a plurality of side-by-side 110

high-voltage coils of different widths located between the low voltage coils, the median lines of the corresponding sides of the several high-voltage coils lying in substantially 5 the same plane.

7. A transformer comprising spaced low-voltage coils and a plurality of side-by-side high-voltage coils of different widths located between the low voltage coils, and connected 10 in a series in which the coils succeed each other in the order of their widths, the median lines of the corresponding sides of the high-voltage coils lying in substantially the same plane.

15 8. A transformer comprising a plurality of pairs of spaced low-voltage coils, and corresponding sets of high-voltage coils of different widths interposed between the coils of each pair, the median lines of the corresponding sides of the several high-voltage coils lying in substantially the same plane.

9. A transformer comprising a plurality of pairs of spaced low-voltage coils, and corresponding sets of high-voltage coils of different widths interposed between the low-voltage coils of each pair, and connected in 25 a series in which the coils succeed each other in the order of their widths, the median lines of the corresponding sides of the several 30 high-voltage coils lying in substantially the same plane.

10. A transformer comprising a plurality of side-by-side coils of different widths connected in a series in which the coils succeed each other in the order of their widths, 35 and in which the high voltage coils are located between the low voltage coils.

11. A transformer comprising a plurality of coils the sides of which are of different 40 widths, the coils being connected in a series in which they succeed each other in the order of the widths of their sides, and in which the coils having narrower sides are located between the coils having wider sides.

45 12. A transformer comprising a plurality of pairs of spaced low voltage coils and corresponding sets of high voltage coils of different widths interposed between the coils of each low voltage pair and connected in a 50 series in which the coils succeed each other

in the order of their widths, and also in which the narrower coils are located between the wider coils.

13. A transformer comprising a plurality of pairs of spaced low voltage coils and corresponding sets of high voltage coils of different widths interposed between the coils of each low voltage pair and connected in a series in which the coils succeed each other in the order of their widths, and also in 60 which the coils of higher potential are located between those of lower potential.

14. A transformer comprising a plurality of pairs of spaced low voltage coils and corresponding sets of high voltage coils inter- 65 posed between the aforesaid low voltage coils of each pair, the high voltage coils being of different widths and being spaced from the low voltage coils in the order of 70 their widths.

15. A transformer comprising a plurality of side-by-side coils the sides of which are of different widths, the coils being connected in a series in which the coils succeed each other in the order of the widths of their 75 sides.

16. A transformer comprising a plurality of pairs of coils the sides of which are of different widths, the coils being connected in a series in which the pairs of coils succeed each other in the order of the widths of 80 their sides.

17. A transformer comprising a plurality of pairs of coils the sides of which are of different widths, the coils being connected in 85 a series in which the pairs of coils succeed each other in the order of the widths of their sides, the coils having narrowest sides being disposed adjacent to each other between the coils of the remaining pairs which are 90 similarly located upon opposite sides thereof and arranged in the order of the widths of their sides.

In testimony whereof, I have hereunto subscribed my name this 23rd day of Sept., 95 1910.

CHARLES LE GEYT FORTESCUE.
